US0D1057202S

(12) **United States Design Patent** (10) Patent No.: **US D1,057,202 S**
(45) Date of Patent: ** Jan. 7, 2025

(54) **POWER EXCHANGE STATION**

(71) Applicants: **AULTON NEW ENERGY AUTOMOTIVE TECHNOLOGY GROUP**, Guangzhou (CN); **SHANGHAI DIANBA NEW ENERGY TECHNOLOGY CO., LTD.**, Shanghai (CN)

(72) Inventors: **Jianping Zhang**, Guangdong (CN); **Hailong Hu**, Guangdong (CN); **Minghou Zhu**, Guangdong (CN); **Libin Wan**, Guangdong (CN); **Xinrui Yu**, Guangdong (CN)

(73) Assignees: **AULTON NEW ENERGY AUTOMOTIVE TECHNOLOGY GROUP**, Guangzhou (CN); **SHANGHAI DIANBA NEW ENERGY TECHNOLOGY CO., LTD.**, Shanghai (CN)

(**) Term: **15 Years**

(21) Appl. No.: **35/518,115**

(22) Filed: **May 5, 2022**

(80) **Hague Agreement Data**

Int. Filing Date: **May 5, 2022**

Int. Reg. No.: **DM/222916**

Int. Reg. Date: **Aug. 19, 2022**

Int. Reg. Pub. Date: **Aug. 25, 2023**

(30) **Foreign Application Priority Data**

Nov. 30, 2021 (CN) 202130790125.X

(51) **LOC (15) Cl.** **25-03**

(52) **U.S. Cl.**

USPC **D25/34**

(58) **Field of Classification Search**

USPC D25/1, 3-35

(57) **CLAIM**

The ornamental design for a power exchange station as shown and described.

DESCRIPTION

1.1: top
1.2: rear
1.3: front perspective
1.4: rear perspective
1.5: right
1.6: front
1.7: left;
2.1: top
2.2: rear
2.3: front perspective
2.4: rear perspective
2.5: right
2.6: front
2.7: left.
